UNITED STATES PATENT OFFICE.

GEORGE W. NEVINS, OF PERRY, NEW YORK.

TRACK-FASTENER.

No. 902,757.

Specification of Letters Patent.

Patented Nov. 3, 1908.

Application filed March 21, 1908. Serial No. 422,479.

To all whom it may concern:

Be it known that I, GEORGE W. NEVINS, a citizen of the United States, residing at Perry, in the county of Wyoming and State 5 of New York, have invented certain new and useful Improvements in Track-Fasteners, of which the following is a specification.

The object of this invention is an improved track fastener which is adapted to 10 effectually secure the rail to a peculiarly formed cross tie with the use of a minimum number of bolts, which is arranged to prevent any spreading of the rail, and in which the bolts employed are relieved of excessive 15 strain.

With this and other objects in view that will more fully appear as the description proceeds, the invention consists in certain constructions, arrangements and combinations 20 of the parts that I shall hereinafter fully describe and then point out the novel features thereof, in the appended claims.

For a full understanding of the invention and the merits thereof, and to acquire a 25 knowledge of the details of construction, reference is to be had to the following description and accompanying drawing, in which:

Figure 1 is a perspective view of a portion 30 of the tie, showing my improved track fasteners applied thereto; Fig. 2 is a detail view in perspective of a clamp; Fig. 3 is a similar view of a brace; Fig. 4 is a top perspective view of one end of the tie, and, Fig. 35 5 is a longitudinal section thereof.

Corresponding and like parts are referred to in the following description and indicated in all the views of the drawing, by the same reference characters.

Referring to the drawing, the numeral 1 40 designates an improved cross tie, which is preferably constructed of metal and which is formed at its side edges with depending flanges 2. This tie is designed to support at 45 its ends two rails 3, and is formed in its upper face, near said ends, with transverse ribs 4 which are flush with the outer edges of the base flanges of the rails, and the inner edges of which form abutments to limit 50 the outward movement of the latter. This tie is formed near its ends with pairs of longitudinally spaced, downwardly converging 55 openings 5 extending therethrough, the openings 5 of each pair being situated on opposite sides of the adjacent rail, and being spaced from the edges of the base flanges

thereof, as shown. These openings 5 are, preferably elongated, and the outermost openings extend through the ribs 4 and divide the latter into two sections, blocks 6 65 being secured to or formed integral with the tie at the extremities thereof, and extending transversely of its upper face, in spaced relation to the ribs 4 and beyond the outer openings 5.

Braces 7 are secured at their outer ends to the extremities of the tie by means of screws or bolts 8, and project inwardly and upwardly, as shown, so as to extend across the outer base flanges of the rails with their inner ends bearing against the webs thereof, the outer extremities of said braces abutting against the blocks 6. Each of these braces is formed with a depending clutching arm 9 which curves downwardly and inwardly and 75 fits in the outer opening 5 and between the sections of the ribs 4, said clutching arm being formed at its inner edge and near its upper end, with an offset portion which constitutes an inwardly facing shoulder 10 and a downwardly facing shoulder 11. The downwardly facing shoulders 11 are arranged to rest upon the portions of the tie between the openings 5 and the adjacent edges of the base flanges of the rails, while the inwardly 85 facing shoulders 10 are adapted to bear against the outer edges of the base flanges of the rails, the outer ends of the braces being preferably inclined as indicated at 12.

Clamps 13 are secured to the cross tie so 90 that the outer ends thereof extend across the inner base flanges of the rail, and are formed with depending clutching arms 14 which curve downwardly and outwardly and are received in the inner openings 5. Each of 95 these clutching arms is formed at its inner edge and near its upper end with an offset portion constituting an inwardly facing shoulder 15 and a downwardly facing shoulder 16, the latter resting upon the portion 100 of the tie between the inner opening 5 and the adjacent edge of the base flange of the rail, and the former being arranged to bear against the inner edge of the base flange of the rail and to hold the same against the brace 7 so as to maintain the proper gage of track. The inner ends of the clamps 13 are 105 preferably inclined as indicated at 18 and are secured to the tie by screws or bolts 17 passing therethrough.

It is to be understood that changes in and modifications of the construction and pre-

portion of the parts, as herein shown and described, may be made within the scope of the appended claims, without departing from the spirit of the invention or sacrificing any of the advantages thereof.

From the above description, in connection with the accompanying drawing, it will be apparent that I have provided a simple, durable and efficient construction of track 10 fastener, which is arranged to effectually secure the rails to the cross tie, which may be easily and cheaply manufactured, and which consists of comparatively few parts that may be readily applied to the tie.

Having thus described the invention, what I claim is:

1. The combination with a cross tie and a rail supported thereon, said tie being formed with openings on each side of the 20 rail and spaced therefrom, of means for securing the rail to the tie, said means comprising track fasteners secured to the tie and engaging the sides of the rail, said track fasteners being formed with depending 25 clutching arms fitting in the openings in the tie and formed in their opposing edges with offset portions constituting shoulders facing the rail and downwardly facing shoulders, the latter resting upon the tie between the openings and the adjacent edges 30

of the rail, and the former bearing against said edges, as and for the purpose specified.

2. The combination with a tie and rails supported at the ends of the latter, said tie being formed near its ends with spaced 35 openings on opposite sides of the rail and with ribs flush with the outer edges of the latter and divided into sections by the outermost openings, said tie being also formed at its ends with blocks on the same side of 40 the rails as the ribs and spaced therefrom, of braces secured to the ends of the tie, with one end engaging the outer base flanges of the rails and bearing against the web portion thereof, and with their other ends abutting against the blocks, said braces being formed with depending clutching arms fitting in the outer openings and between the sections of the ribs, and clamps secured to the tie and formed with depending clutching 50 arms received in the inner openings, said clamps engaging the inner base flanges of the rails and being arranged to hold the latter against the braces.

In testimony whereof I affix my signature 55 in presence of two witnesses.

GEORGE W. NEVINS. [L. s.]
